and one-third to Olive Daniels, Denver, Colo.

Application January 3, 1944, Serial No. 516,895

9 Claims. (Cl. 179—104)

This invention relates to improvements in sound transmitters of the general type employed in connection with telephones, hearing aids, broadcasting and sound detection and transmissions in general.

In the ordinary telephone transmitter, the vibrations of a diaphragm are transmitted to a carbon granule resistor in such a way that their resistance to the flow of an electric current varies with the amplitude of the diaphragm vibrations. When the pressure increases, the carbon granules are packed more closely together, whereupon the resistance to the flow of an electric current decreases and when the pressure is decreased, the resistance increases. In this manner a constant potential electric circuit comprising the carbon granules will produce a current that varies in accordance with the amplitude of the sound waves striking the diaphragm.

The variation in the resistance of the carbon granules or microphone is due, in greater part, to the pressure which forces the granules into closer contact, thereby reducing the resistance. It is well known that the resistivity of carbon decreases with pressure and that the resistance of a circuit can therefore be varied by changing the pressure applied to a portion of a circuit conductor containing carbon. This property was the basis of the Edison microphone transmitter. The use of carbon granules followed that of the solid carbon microphone element of Edison and is now in common use. The variation in the resistance of a carbon granule resistance element is due in part to the negative pressure resistivity and in part to the fact that the pressure urges the granules into closer contact.

It is evident that the pressure variations due to the impact of the sound waves on the transmitter diaphragm cannot produce any great force variations and that therefore the variations in the current are small.

It is the object of this invention to produce a transmitter of the carbon microphone type in which the variations in the current will be amplified by magnetic means to such an extent that stronger signals will be produced.

This invention, briefly described, consists in passing the transmitter or microphone current through a coil surrounding either a permanent magnet core or a soft iron magnet core in such a way as to vary the magnetic flux in accordance with the amplitude of the transmitter diaphragm vibrations and to position the carbon resistance element between one pole of the electromagnet and an armature so that the increase

in the current due to the increased pressure exerted on the carbon resistor will cause an increase in the strength of the magnet with a corresponding increase in the magnetic pull on the armature. This increased pull will produce an increase in the pressure applied to the carbon resistor element and consequently a decrease in its resistance and an increase in the current. As soon as the diaphragm reverses so as to reduce the pressure, the current and magnetic pull will also decrease.

Another object is to produce a transmitter of the type described in which the usual carbon granules shall be replaced by granules having a magnetic core coated with carbon, or which are made from a mixture of carbon and iron powder. Such granules are magnetic and when subjected to the action of a magnet they tend to compress or be urged against each other so as to augment the compression due to the vibrating diaphragm.

In order to describe the invention with greater detail and particularly so that it may be more readily understood, reference will now be had to the accompanying drawing in which the invention has been illustrated and in which:

Figure 1 is a transverse section of a transmitter taken on line 1—1, Figure 2;

Figure 2 is a diametrical section taken on line 2—2, Figure 1;

Figure 3 shows a modified form of the invention;

Figure 4 is a diametrical section through a granule formed from a mixture of carbon and iron powder; and

Figure 5 is a section showing a granule formed from a magnetic core with a coating of carbon.

The granules shown in Figures 4 and 5 have been greatly enlarged on the drawing, but are to be of the usual size employed in telephone transmitters.

In the drawing reference numeral 10 designates a cup-like member of insulating material, such as hard rubber, or some suitable plastic and reference numeral 11 designates a cover secured to the open end of member 10 by means of a threaded connection 12. A sheet metal diaphragm 13 is positioned against the open end of member 10 and held in position by means of the cover 11, which is provided with an internally extending flange 14 for this purpose. A U-shaped magnetic strap 15 of soft iron, is positioned in the member 10 with its ends in the vertical grooves 16 provided therefor in the walls of member 10 and is secured to the bottom

of the latter by means of screws 17. Extending upwardly from the base of member 15 is a magnetic core 18 which may be made from soft iron, or from hard steel in the form of a permanent magnet. If a permanent magnet is employed, it is preferably of the type comprising an aluminum alloy, which is marketed under the trade name of "Alinco," or some other alloy suitable for permanent construction.

Core 18 may be secure to strap 15 by means of a threaded connection 19, as shown in Figure 12, or in any other suitable way. Surrounding the core 18 is a coil of wire which has been designated by reference numeral 20. This coil is wound in the form of a spool in the ordinary manner, the spool being so constructed that it can be readily positioned on the core during the manufacture. Reference numerals 21 and 22 designate the ends of the spool. Secured to the top of the core is a cup 23 of nonmagnetic material. A carbon plate 24 is positioned in the bottom of cup 23 and one end of the wire 21 is electrically connected with plate 24. Positioned in the cup and resting on plate 24 is a large number of carbon granules 25. On top of the granules is a carbon plate 26 on which is supported a soft iron armature 27. This armature terminates in a conical portion 28 against the apex of which the diaphragm 13 rests. Secured to the inner surface of one of the vertical arms of the U-shaped member 15 is a plate 29 of insulating material. This has been shown as held in place by means of screws 30 and 31. A spring 32 is secured at one end to the insulating member 29 by means of a screw 33 and the upper end of this spring is provided with an opening through which the center portion of the armature 27 extends. A screw 34 is threadedly connected with the insulating plate 29 and extends through an opening 35 in the strap 15. The inner end of screw 34 engages the surface of spring 32 and by means of this screw the pressure exerted by the spring on the armature 27 can be adjusted.

A wire 36 is connected with the spring 32 and terminates in the receiver hook switch contact 37. The other contact 38 of this switch extends to one pole of a battery 39. The coil 20 terminates in a wire 40 that is connected to one terminal of the primary winding 41 of a transformer from which conductor 42 extends to the battery. The secondary 43 of the transformer is connected to the winding 44 of a telephone receiver whose diaphragm has been designated by reference numeral 45. A spring 46 is connected with the receiver hook 47 in such a way that when the receiver is off from the hook, the switch is closed.

Let us now assume that with the parts arranged as shown in Figure 2 and described above, a sound of varying intensity is emitted adjacent the opening 48 in cap 11. The sound waves impinging on the diaphragm 13 cause the latter to vibrate whereupon the carbon granules 25 become subjected to a variable pressure. Current from the battery 39 flows through the spring 32, through the carbon granules through coil 20 and through the primary 41 and the variations in this current due to the variations in the pressure exerted on the carbon granules, produce an induced current in the secondary 43 which causes a variation in the magnetic flux from the permanent magnet 49 of the receiver. The operation just described is analogous and almost identical with that of the ordinary telephone transmitter, but differs therefrom in these important particulars.

First, the current that flows through the carbon granules also flows through the coil surrounding the core 18 and if the latter is a permanent magnet, it causes a variation in the magnetic flux. Second, this transmitter is provided with an armature 27 which is acted upon by the magnetic flux from the permanent magnet 18 and therefore when the diaphragm moves downwardly, when viewed as in Figure 2, it increases the compression on the carbon granules thereby, producing an increased current, this increased current will further increase the magnetic flux and the resultant pull on the armature, thereby further compressing the carbon granules allowing more current to flow which increases the magnetism producing further compression.

At this place it will be pointed out that where core 18 is in the form of a permanent magnet, the battery must be so connected that the current in coil 20 will increase the magnetism so that an increased current will produce an increased magnetic pull. If core 18 is of soft iron, such as a bundle of very fine soft iron wires or from electrolytic iron powder which has been compressed, the direction of current flow in coil 20 is immaterial.

From the description just given it will be apparent that whenever the diaphragm moves downwardly so as to compress the carbon granules and thereby reduce the resistance of the circuit, due to the better contact afforded between the particles when thus compressed and due further more to the characteristic of carbon which decreases its resistivity with pressure, an increased current will flow through the coil 20, thereby increasing the pressure which, in turn, increases the current and this amplification is transmitted through the transformer to the receiver. As soon as diaphragm 13 moves upwardly, the pressure on the carbon granules immediately decreases, thereby increasing the resistance and decreasing the current.

Due to the fact that the pressure responsive resistance is in series with coil 41, the battery 39 and the magnet coil 18, the variations in resistance, due to the pressure variations, are small compared to the resistance of the entire circuit. The variations in resistance due to the action of the diaphragm causes a large increase in the resistance when the diaphragm moves upwardly, when viewed as in Fig. 2, and this removes any possibility of the parts locking due to the progressive increase in current resulting from the decrease in the resistance produced by the magnetic attraction.

Particular attention is called to the construction just described in which the current through the carbon microphone transmitter causes a variation in the compression forces so as to produce a corresponding variation in the resistance of the carbon element of the circuit. By means of this interaction an amplifying function is obtained.

In the construction shown and described above, ordinary carbon granules can be employed because the magnetic attraction of the permanent and electromagnet acts on the armature 27 to produce the result described. Better and more marked results can be obtained, however, by substituting for the ordinary carbon granules, other granules having magnetic properties. These granules may be made from a mixture of carbon powder and powdered iron, as indicated in Figure 4, such powder mixture being formed into granules by submitting the powder to pressure in suitable molds. Another way of producing these

granules is to take small pieces of soft iron, such as have been designated by reference numeral 50 and covering them with a layer 51 of carbon. This layer may be applied in several different well known ways, as, for example, it may be covered with a hydrocarbon oil and carbonized or subjected to heat in an atmosphere containing carbon or subjected to an electrolytic plating operation by means of which carbon will be electrolytically deposited thereon.

When granules having magnetic properties are employed in place of the pure carbon granules, it is evident that the magnetic attraction will be exerted on the separate granules, as well as on the armature 27. In fact with magnetic granules it is possible to replace the soft iron armature 27 with one made from aluminum or other nonmagnetic material. In either case the member corresponding to armature 27 should be conductive so that current may flow from the spring 32 to the carbon plate 26.

Since carbon has the property of reducing its resistance when subjected to pressure, it is possible to dispense with the carbon granules and allow the two plates 24 and 26 to come into direct contact as shown in Figure 3. In this case the cup 23 can be made very shallow. With the construction shown in Figure 3, the magnetic attraction is exerted on the armature 27 and this varies the compressive forces applied to the carbon in a manner analogous to the well known Edison carbon microphone transmitter.

The U-shaped member 15 forms a part of the magnetic circuit, another part of which is formed by the diaphragm 13, which is preferably from magnetic material. Thin sheets of insulating material like that designated by reference numeral 52 in Figure 2 are interposed between the diaphragm 13 and the ends of the strap 16, or other suitable means is provided for electrically insulating the diaphragm from contact with any current carrying parts.

The transmitter described above and shown on the drawing can be employed in ordinary telephone circuits or in any other sound transmitting system where amplification is desired. It is believed to be of particular importance in connection with hearing aids for slightly deaf people, because this amplifying property makes it possible to dispense with the ordinary electronic amplifying tubes now incorporated in such hearing aids. With this simple construction amplification can be obtained without complicated and expensive mechanism, thereby reducing the first cost and reducing the subsequent cost of upkeep.

Although applicant cannot, at this time, enumerate all uses to which this invention might be put, it is to be understood that he does not desire to be limited strictly to the uses specified.

Although the invention has been illustrated of certain shape and size, it is, of course, to be understood that this is merely for the purpose of description and that the invention is entirely independent of the specific shape and size in which it is embodied.

Having described the invention what is claimed as new is:

1. A sound transmitting and reproducing device comprising, in combination, an electromagnet, an armature comprising an assemblage of granules containing carbon and iron, means for circulating a direct current through the armature and the winding of the electromagnet, and a sound responsive device operatively associated with the armature for varying the pressure there-

on in accordance with sound waves, whereby a corresponding variation in the current is effected.

2. A sound amplifying device comprising, in combination, an electromagnet comprising a core and a magnetizing coil, an armature operatively associated with the core and spaced therefrom, a pressure responsive resistance element positioned between the core and the armature to be compressed by the latter when it is attracted

10 by the electromagnet, an electric circuit comprising the resistance element and the magnet coil in series, a source of direct current in series in the circuit, and means comprising a sound responsive diaphragm for moving the armature to vary the compression of the resistance element.

15 3. A sound transmitter and amplifier comprising a base, a magnetic core carried thereby, an armature carried by the base and spaced from the magnetic core, a pressure responsive resistance element positioned between the core and the armature in position to be compressed when the armature moves towards the core, a magnetizing coil enclosing the core, a source of direct current, a circuit comprising the pressure responsive re-

20 sistance, the current source and the wire coil forming a current path, and means independent of the action of the magnetism from the core and coil for moving the armature towards and away from the core to vary the resistance of the resistance element, whereby when the armature approaches the core, the current in the coil will increase, producing a greater pressure.

25 4. An amplifying sound transmitter comprising a base, a diaphragm supported thereon for vibration in response to sound waves, an electromagnet comprising a magnetizing core and a coil supported on the base, the end of the core being spaced from the diaphragm, a pressure responsive resistance element so positioned between the

30 core and the diaphragm that the latter exerts a compressive force thereon, means for flowing an electric current in series through the resistance element and the coil, and an armature positioned between the core and the diaphragm and so associated with the core that the magnetic pull thereon will compress the element and reduce its resistance, thereby increasing the flow of current and the magnetic pull.

35 5. A sound amplifying transmitter comprising, in combination, a base, a magnet core secured thereto, a magnetizing coil surrounding the core, an armature movably connected with the base and spaced from the core, a resistance element having a negative pressure resistance characteristic, positioned between the armature and an end of the core, said element comprising carbon granules, means comprising a sound responsive dia- 40 phragm for urging the armature towards the core and against the carbon granules, an electric circuit comprising the magnetizing coil, the carbon granules and a source of direct current in series, and means comprising the diaphragm for moving the armature in response to sound waves, whereby the current in the magnet coil will be varied, producing a corresponding variation in the force acting on the armature.

45 6. In a sound transmitter an amplifying element comprising a core of magnetic material, a magnetizing coil surrounding the core, a cup of insulating material attached to one end of the core, a resistance element positioned in the cup, said element comprising an assemblage of granules formed from carbon and iron, an armature spaced from the core by the resistance element, 50 means for urging the armature against the re-

sistance element, an electric circuit comprising the resistance element, the magnetizing coil and a source of direct current connected in series, means for vibrating the armature in response to sound waves, whereby the resistance of the element will be varied and whereby the compressive action will be increased by the increased attraction of the magnet on the magnetic granules.

7. A sound amplifying transmitter comprising, in combination, a base, a magnet core secured thereto, a magnetizing coil surrounding the core, a pressure responsive resistance element positioned between the armature and an end of the core, said element comprising granules containing carbon and a magnetic material, means comprising a sound responsive diaphragm for exerting a pressure on the carbon granules, an electric circuit comprising the carbon granules, and a source of direct current in series, and means comprising the diaphragm connected with the base and with the resistance element for varying the pressure on the granules in response to sound waves, whereby the current in the magnet coil will be varied producing a corresponding variation in the magnetic force acting on the granules.

8. A sound amplifying device comprising, in combination, a base, a core secured thereto, a diaphragm connected with the base and spaced from one end of the core, a magnetizing coil surrounding the core, a resistance element positioned between the core and the diaphragm, said element

comprising an assemblage of granules formed from carbon and iron, means positioned between the diaphragm and the granules for exerting a pressure on the granules and for varying the pressure in accordance with the vibrations of the diaphragm in response to sound waves, and a source of direct current, a circuit comprising the resistance element, the magnetizing coil and the source of current in series, whereby the varying

5 resistance of the resistance element, in response to diaphragm vibrations, will produce a corresponding variation in the current and in the magnetic flux, whereby the action of the latter on the magnetic granules will vary the resistance inversely with the current.

9. An amplifying device, comprising, in combination, a permanent magnet core, a coil surrounding the core, a pressure responsive resistance element comprising granules having an iron 10 core covered with carbon positioned adjacent the core, means responsive to the flux of the magnet for exerting a compressive force on the resistance element, which varies with the intensity of the magnetic flux, a circuit comprising a source of 15 direct current, the resistance element and the coil in series, means independent of the magnet for varying the compression of the resistance element in accordance with sound waves, whereby the current in the circuit and the magnetic flux 20 will vary.

WILLIAM P. CARSTARPHEN.
